CLAIM

The ornamental design for a belt adjuster for bag, as shown and described.

DESCRIPTION

FIG. 1 is a front, top, and right side perspective view of a belt adjuster for bag, showing our new design;
 FIG. 2 is a front view thereof;
 FIG. 3 is a back view thereof;
 FIG. 4 is a left side view thereof;
 FIG. 5 is a right side view thereof;
 FIG. 6 is a top view thereof;
 FIG. 7 is a bottom view thereof;
 FIG. 8 is a cross-sectional view taken along line 8-8 shown in FIG. 2;
 FIG. 9 is a back, top, and left side perspective view thereof; and,
 FIG. 10 is a reference view showing the belt adjuster for bag in use.
 The long dash short dash broken lines and arrows shown in FIG. 2 are used to identify the cross-sectional view and form no part of the claimed design. The evenly spaced broken lines shown in FIG. 10 depict environment and form no part of the claimed design.
